UNITED STATES PATENT OFFICE.

PAUL P. HEIN, OF NEW YORK, N. Y.

HEADLIGHT-DIMMER.

1,346,708.

Specification of Letters Patent.

Patented July 13, 1920.

Application filed June 26, 1918. Serial No. 242,025.

To all whom it may concern:

Be it known that I, PAUL P. HEIN, a citizen of the United States, and a resident of the city of New York, borough of Manhattan, in the county and State of New York, have invented a new and Improved Headlight-Dimmer, of which the following is a full, clear, and exact description.

This invention relates to headlights such as are commonly used on road vehicles, and has particular reference to means to nullify the objectionable glare that commonly accompanies a powerful lamp of this character.

Among the peculiar objects of this invention is to provide a device with means for carrying it in substantially vertical position sufficiently far in front of the lamp structure or lens as to provide for an appreciable amount of laterally and rearwardly projected light for illumination of the roadway at the sides of the vehicle and also to illuminate the vehicle itself, enabling thereby any person located at a distance in front of the vehicle to readily recognize or discern the nature of the vehicle or to read the license number thereon.

Another object of the invention is to provide an attachment for a standard lamp, the same constituting a device adapted to be readily applied to any existing headlight, and yet being possessed of qualifications to meet the demands of the law or municipal regulations regarding the intensity of the light from the lamp within the structure.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical central section of a standard headlight equipped with my improvement, the sectional part of the view being substantially on the line 1—1 of Fig. 2.

Fig. 2 is a rear elevation of my improved attachment or as it would be seen from the line 2—2 of Fig. 1;

Fig. 3 is a detail perspective view of the frame portion of my improvement.

Fig. 4 is a horizontal sectional detail on the line 4—4 of Fig. 2.

The laws and ordinances of various cities or municipalities requiring some means to nullify or reduce the offensive glare of headlights whereby pedestrians or others who may be positioned in front of an approaching automobile are practically blinded or at least seriously confused, I provide a means either as a part of an automobile lamp or as an attachment to be applied to a standard lamp casing whereby the glare from the lamp bulb is either nullified or reduced to such an extent as to be unobjectionable and yet sufficient light is projected both ahead of the vehicle and laterally thereof to meet all requirements in practice.

Referring now more specifically to the drawings I show at 10 a shield made of any suitable sheet material preferably of a translucent nature, such as white or tinted celluloid or the like, but having a white bright or reflecting clear surface. This shield as indicated best in Fig. 2 is in the nature of a circular segment preferably just a little larger than a semi-circle and having a radius somewhat greater than that of the lens or window 11 ahead of and spaced from which the shield is adapted to be supported. The shield may be held in advance of the lamp window or lens 11 by any suitable means providing for free space between the lens and the shield for the purpose of dispersing the light laterally so as to illuminate the roadway or even the vehicle itself to a better advantage than is usual.

Among the various means that may be employed for supporting the shield as indicated, I provide a frame 12 shown in detail in Fig. 3 as comprising a crown 13 in the nature of a flat ring adapted to be gripped between the periphery of the lens 11 and the outer lamp casing flange 14 where it will be held in reliable position. This frame includes also a series of legs 15 and 16 each having a foot 17 bent at right angles to the leg and each foot having a tapped hole 17' therethrough. This frame 12 is shown as being formed by cutting or stamping from a single piece of sheet metal, the legs being bent forward at right angles to the plane of the ring 13 and so may project forward parallel to one another ahead of the main portion of the lamp. The feet 17 are bent outward from the axis of the device. The side leg 16 as indicated plainly in Fig. 1 is

shorter than the other two legs so that the side portion of the shield secured thereto is inclined somewhat rearward toward the lamp casing and thereby two important advantages are realized, as follows: First, the side portion of the shield supported by the leg 16 and curved as indicated renders the shield much stiffer and stronger than if it were left flat and consequently much lighter and thinner stock may be used for the purpose, and secondly, while it is desirable that the main portion of the shield or that portion that lies directly in front of the lamp casing should be substantially flat and parallel to the front edge of the casing, the function of reflecting the light laterally and rearwardly is much better carried out by the provision of the curved edge portion and also by the fact that the edge portion projects materially beyond the scope of the lamp lens. The shield is provided with holes registering with the holes 17' in which screws 18 or similar fasteners are adapted to project so as to connect the shield to the frame.

Each of the lamps or headlights equipped with one of my improvements has the full circular portion of the shield on the left side so as to obstruct the direct rays of the light from the view of any person approaching on the road and whom the driver of the vehicle having the lamp will meet and pass by turning to the right. The upper portion of the shield has an extension 10' over toward the right side of the lamp to obstruct somewhat more of the light emerging from the top of the reflector. That portion, however, adjacent to the axis of the lamp is preferably vertical as shown at 10^a and lies just to the right of the lamp filament. At the right side of the edge 10^a there is ob-

served sufficient space unobstructed to permit sufficient light from the reflector to illuminate the roadway ahead, while a considerable portion of the light striking against the rear reflecting surface of the shield will be spread out laterally and rearwardly so that anyone in front of the vehicle will be able to see clearly the nature of the vehicle and plainly and easily read the license number on the front of the machine. The nature of the shield itself should be such as to permit a soft diffused light to pass directly therethrough and still prevent any possible glare from the lamp filament. The shield as indicated covers all of the filament and a large portion of the reflector. By no reasonable possibility therefore can any person on the road see the lamp or lamp bulb directly.

A device made in accordance with this invention is not only cheap to construct, but may be easily applied to any standard lamp casing and serves the purpose with a high degree of efficiency.

I claim:

In a dimmer for headlights, the combination of a translucent glare reducing shield in the form of a segment of a circular disk, and means extending forward from the lamp casing serving to hold the shield in front of and in spaced relation to the front portion of the casing, the rear surface of the shield being of a reflecting nature whereby a certain portion of the light will be dispersed laterally and therefrom between the shield and the lamp casing said shield lying essentially in a plane parallel to the front edge of the lamp casing but having a side portion curved rearward toward and yet spaced from the lamp casing.

PAUL P. HEIN.
